UNITED STATES PATENT OFFICE.

CHARLES H. McCUALEY, OF BALTIMORE, MARYLAND.

DESIGN FOR A PAIL OR BUCKET.

SPECIFICATION forming part of Design No. 25,727, dated June 30, 1896.

Application filed May 2, 1896. Serial No. 590,032. Term of patent 3½ years.

To all whom it may concern:

Be it known that I, CHARLES H. McCUALEY, a citizen of the United States, residing at Baltimore, in the State of Maryland, have invented and produced a new and original Design for a Bucket or Pail, of which the following is a specification, reference being had to the accompanying drawing, forming a part hereof.

10 The drawing is a perspective view of a pail or bucket, showing my design.

The bucket is circular, as seen from either end, and of greater diameter at the top than at the bottom.

15 The leading feature of my design consists in a pictorial representation of two children

playing with buckets and shovels. One child has the bucket on her arm and her shovel is held so that its edge touches the ground. The other child holds the shovel over his left shoulder and carries the bucket in his right hand, the arm of which hangs at full length.

The pictorial design is made up of short disconnected lines, such as are produced by a stencil.

20 25 What I claim is—

The design for a pail or bucket, substantially as herein shown and described.

CHAS. H. McCUALEY.

Witnesses:

JOHN L. HEBB,

DANL. FISHER.
